UNITED STATES PATENT OFFICE

152,557

DESIGN FOR A PORTABLE PHOTOGRAPHIC LABORATORY

Clayton M. Nielsen, Alhambra, Calif.

Application April 28, 1947, Serial No. 138,659

Term of patent 3½ years

(Cl. D61—1)

To all whom it may concern:

Be it known that I, Clayton M. Nielsen, a citizen of the United States, residing at Alhambra, in the county of Los Angeles and State of California, have invented a new, original, and ornamental Design for a Portable Photographic Laboratory, of which the following is a specification, reference being had to the accompanying drawings, forming part thereof.

Figure 1 is a perspective view of the portable photographic laboratory embodying my new design illustrating the same in closed or collapsed position; and Fig. 2 is a perspective view of the same illustrating it in its extended or set up position.

I claim:

The ornamental design for a portable photographic laboratory, as shown.

CLAYTON M. NIELSEN.
